UNITED STATES PATENT OFFICE.

JENS ORTEN BOVING, OF WESTMINSTER, LONDON, ENGLAND.

ABSORPTION REFRIGERATING APPARATUS.

Application filed December 22, 1926, Serial No. 156,275, and in Great Britain May 21, 1926.

This invention relates to refrigerating apparatus of the reversing absorption type, that is to say an apparatus in which a volatile refrigerant is alternately driven over by 5 heat from a boiler-absorber containing an absorbent liquid for the volatile refrigerant, into and is liquefied in, a condenser or combined condenser and evaporator, and, on cooling the boiler-absorber, evaporates in 10 and is withdrawn from the evaporator and becomes re-absorbed in the absorbent liquid in the boiler-absorber.

More particularly the invention relates to pivoted reversing absorption refrigerating 15 apparatus wherein rocking, resulting from the displaced weight of the transferred volatile refrigerant, effects the change in the temperature conditions of the boiler-absorber so as to cause automatic reversal of 20 the action of the apparatus.

The invention provides a rocking reversing absorption refrigerating apparatus wherein the communication between the boiler-absorber and the evaporator is so arranged that the space in which the evaporator is located can be constantly isolated from the space in which the boiler-absorber is located, thus avoiding direct interchange of 25 heat between these two spaces and consequent impairment of the refrigerating action.

For this purpose, the communication between the boiler-absorber and the evaporator of a rocking reversing absorption type of 30 refrigerating apparatus extends axially along the pivot about which the apparatus rocks. Thus with the evaporator located within a cooling safe and the boiler-absorber located outside such safe, no aperture is required in the intervening wall of the safe 35 other than the aperture constituting the journal bearing of the apparatus, which aperture is constantly closed by the pivot journal.

40 The condenser may constitute or form part of the pivot of the apparatus.

Various embodiments of the apparatuses according to the invention are diagrammatically illustrated on the accompanying 45 drawings, in which:—

Fig. 1 is a sectional side elevation of one apparatus in the heating and condensing position, and

Fig. 2 is a corresponding plan.

Fig. 3 is a side elevation showing this 55 apparatus in the evaporating re-absorbing position.

Figs. 4 and 5 are side elevations of another apparatus in different positions.

Referring more particularly to Figs. 1 60 to 3:

a is a boiler-absorber and *b* is an electric heater therefor. *c* is a perforated pipe whereby refrigerant vapour, driven off by heat from the absorbent liquid in the boiler 65 *a*, is led to a pipe *d* of larger section which acts as a steam trap and provides a pocket *d*¹, the purpose of which is described later.

e is a condenser into which the refrigerant vapour passes from the pipe *d* by a lateral 70 branch *d*². The condenser *e* is traversed by a cooling pipe to which cooling water is admitted by a pipe *f* and flows out by a pipe *g*.

h is the evaporator to which the condenser *e* is connected by a pipe *i*. 75

The boiler-absorber *a* and condenser *e* and the evaporator *h* are conjointly pivoted to rock about an axis *x*—*x* coaxial with a portion of the pipe *i*, and, as can be seen in Fig. 2, the boiler-absorber *a* together with the 80 condenser *e* projects on one side of this axis whilst the evaporator *h* projects on the opposite side thereof. By virtue of this arrangement the boiler-absorber *a* can be located outside a cooling safe *j* (Fig. 2) and 85 the evaporator *h* located inside the safe *j*, whilst the pipe *i* extends through the wall of the safe *j* and constitutes a journal on which the apparatus can rock without there being any unclosed opening through the 90 wall of the safe *j*.

The evaporator *h* is divided by a partition *h*¹ bridged by a syphon *h*². The refrigerant liquefied in and trickling from the condenser *e* therefore first slowly rises in the 95 compartment *h*³ of the evaporator *h* nearer the rocking axis *x*—*x* until it floods the syphon *h*² when the liquid refrigerant will abruptly flow through the syphon *h*² into the remoter compartment *h*⁴ of the evaporator *h*. By this time it is arranged that approximately all the refrigerant will have 100 been driven off from the boiler-absorber *a*.

The liquid refrigerant flowing into the compartment *h*⁴ of the evaporator *h*, over-balances the apparatus and causes it to rock 105

and assume the position shown in Fig. 3, in which it is arrested by the evaporator h encountering a stop k^2 , the boiler-absorber a having left a stop k^1 .

5 In this position of the apparatus the supply of electric current to the heater b is interrupted by the rotation of a contact on a switch disc b^1 on the pivot of the apparatus, from a brush b^2 connected in one of the 10 electric leads b^3 of the heater b . Also cooling water is supplied to a cooling coil l in the boiler-absorber a whereby the latter is cooled to reduce the pressure therein and promote evaporation of the refrigerant in 15 the evaporator h and its withdrawal therefrom and reabsorption in the absorbent liquid in the boiler-absorber a .

The cooling water is supplied to the cooling coil l of the boiler-absorber a by a pipe 20 m , which in the then position of the apparatus has become connected by a three-way cock n (Fig. 2) to the outlet pipe g from the condenser e , alternatively to such outlet pipe g being connected to a drain pipe o .

25 The cooling water leaves the cooling coil l of the boiler-absorber a by an outlet l^1 .

The pipe f for supplying the cooling water to the condenser e is brought to the apparatus coaxially with the axis $x-x$ of the 30 pivot journal portion of the pipe i , and the three-way cock n is also coaxial and turns therewith.

The boiler-absorber a is formed with two compartments a^3 , a^4 separated by a partition a^1 bridged by a syphon a^2 , similarly to the delaying arrangement provided in the evaporator h . The syphon a^2 of the boiler-absorber a , however, acts both at the commencement and at the termination of the 40 evaporating and re-absorbing phase of the apparatus. The syphon a^2 is submerged by the absorbent liquid in the boiler-absorber a when the latter is in the position shown in Fig. 1. Consequently, on the boiler-absorber 45 moving into the position shown in Fig. 3, the already flooded syphon a^2 transfers absorbent liquid from the compartment a^4 to the compartment a^3 so that such liquid is all subjected to the bubbles of refrigerant vapour which arise from the then submerged 50 perforated pipe c . The syphon a^2 then remains inactive until again flooded by the increase in the volume of the liquid in the compartment a^3 due to the re-absorption of the refrigerant vapour. As the compartment a^3 in which the perforated pipe c by which the evaporated refrigerant returns to the boiler-absorber a and bubbles up through the absorbent liquid therein, is located nearer 55 the pivotal axis x , over-balancing of the apparatus due to increase of liquid in the boiler-absorber a will be delayed until the 60 syphon a^2 abruptly transfers liquid to the remoter compartment a^4 .

65 p is a counter-weight for initially so bal-

ancing the apparatus that rocking is delayed until the above described delayed syphonic action occurs in either direction.

In the evaporating position, Fig. 3, the evaporator h may, as shown, be arranged to 70 dip into and cool brine contained in a tank q within or alternative to the safe j .

In the heating position, the pipe d extends obliquely upwards from the pipe c which enters the boiler-absorber a , whilst the condenser e extends obliquely downwards from the lateral connecting pipe d^2 , thereby providing drainage in the appropriate directions of condensed steam back into the boiler-absorber a and of condensed refrigerant into the evaporator h .

The perforated portion of the pipe c is of such extent and so located within the boiler-absorber a , that in the heating position, Fig. 1, some of the perforations are above the 85 level of the absorbent liquid in the boiler-absorber a , whereas in the re-absorbing position, Fig. 3, these perforations are all submerged in this liquid. Also in the re-absorbing position the pipes c d still extend externally above the absorbent liquid so precluding the latter flowing into the evaporator h . Thus any necessity for an alternative communication between the boiler-absorber a and the pipe c provided with a non-return 90 valve, is avoided.

Like in all absorption systems, a certain amount of steam is formed and goes over with the refrigerant from the boiler-absorber into the evaporator h where it becomes condensed. By rotating the apparatus into the position shown in Fig. 5, after removal of the stop k^1 , any residual liquid in the evaporator h can be drained into the above mentioned pocket d^1 of the steam trap pipe d , 105 when by swinging the apparatus into the position shown in Fig. 1 it will drain back into the boiler-absorber a .

As shown in Figs. 4 and 5, the condenser e may be coaxial with the pivotal axis x and 110 constitute the pivot journal.

The angle through which the apparatus rocks is not limited to the 90° shown, but depends upon the design of the apparatus. It may here be mentioned that the apparatus 115 can be put out of action by turning the apparatus sufficiently beyond the normal limits of turning, for instance into the draining position shown in Fig. 5.

The means for heating need not be electric nor move with the boiler, for in a rocking system the boiler-absorber can obviously move on to and away from a gas or oil burner or an electric or other heater, with or without providing for automatic control of 120 the heating medium.

The condenser and evaporator may as in other apparatuses of the reversing absorption type be combined into a single unit, in which case, however, provision should be 125

made for interruption of the supply of cooling water thereto during the evaporation of the liquid refrigerant therein.

I claim:

5. 1. In a rocking reversing absorption refrigerating apparatus, a boiler-absorber, condenser and evaporator, intercommunication means between said boiler-absorber and said condenser and evaporator, and means restraining and eventually abruptly effecting the distribution of liquid in said boiler-absorber.

10. 2. In a reversing absorption refrigerating apparatus, a boiler-absorber, condenser and evaporator, intercommunication means between said boiler-absorber and said condenser and evaporator, and means restraining and means eventually abruptly effecting the distribution of liquid in said evaporator.

15. 3. In a rocking reversing absorption refrigerating apparatus, a boiler-absorber, condenser and evaporator, intercommunication means between said boiler-absorber and said condenser and evaporator, and a barrier restraining and a syphon abruptly effecting distribution of liquid in said boiler-absorber.

20. 4. In a reversing absorption refrigerating apparatus, a boiler-absorber, condenser and

evaporator, intercommunication means between said boiler-absorber and said condenser and evaporator, and a barrier restraining and a syphon abruptly effecting distribution of liquid in said evaporator.

25. 5. In a rocking reversing absorption refrigerating apparatus, a pivot of said apparatus, a boiler-absorber, a partition within said boiler-absorber, a syphon bridging said partition, a condenser, an evaporator, and intercommunication means between said evaporator, said condenser and said boiler-absorber delivering into said boiler-absorber on the side of said partition nearer said pivot of said apparatus.

30. 6. In a rocking reversing absorption refrigerating apparatus, a pivot of said apparatus, a boiler-absorber, a condenser, an evaporator, a partition within said evaporator, a syphon bridging said partition, and intercommunication means between said boiler-absorber, said condenser and said evaporator delivering into said evaporator on the side of said partition nearer said pivot of said apparatus.

35. In testimony whereof I have signed my name to this specification.

JENS ORTEN BOVING.
